[57] CLAIM

The ornamental design for a toy vanity, substantially as shown and described.

DESCRIPTION

FIG. 1 is a top right front perspective view of a toy vanity showing my new design, the left side being substantially a mirror image of the right side;
FIG. 2 is a rear elevational view thereof;
FIG. 3 is a bottom plan view thereof; and
FIG. 4 is a top plan view thereof.

The cover is shown open in FIGS. 1-3 and closed in FIG. 4.

FIG. 2

FIG. 3

FIG. 4
